H. C. KARR,

WATCH STAND.

APPLICATION FILED FEB. 18, 1921.

1,384,071.

Patented July 12, 1921.

UNITED STATES PATENT OFFICE.

HENRY C. KARR, OF WASHINGTON, DISTRICT OF COLUMBIA, ASSIGNOR OF ONE-FIFTH TO EMIL BÖNNELYCKE, OF WASHINGTON, DISTRICT OF COLUMBIA.

WATCH-STAND.

1,384,071.

Specification of Letters Patent. Patented July 12, 1921.

Application filed February 18, 1921. Serial No. 446,067.

To all whom it may concern:

Be it known that I, HENRY C. KARR, a citizen of the United States of America, residing at Washington, District of Columbia, 5 have invented certain new and useful Improvements in Watch-Stands, of which the following is a specification.

This invention relates to watch stands; and its main object, briefly stated, is the 10 production of an improved article or device of the character indicated which may be constructed at a minimum cost and without requiring the use of complicated machinery; such article serving to effectively support a 15 watch in substantially upright position so that the time may be read from its dial at a glance, and without danger of the watch slipping out of the holder or of the latter itself tipping over in any direction.

20 The invention also resides in the provision of a holder as above described which is applicable to, and capable of use with, watches of widely different styles and sizes and which is so constructed that the watch 25 may be easily and quickly engaged and disengaged with and from the holder and, when in place therein, will be held in position by the holder.

Other and further improved and advantageous features will be set forth in the following description; but it will be understood that the precise disclosure given imposes no limitation upon the invention, since the latter is manifestly susceptible of modification and change within its scope as hereinafter claimed.

According to the invention, the holder 30 comprises a strip or blank of substantially symmetrical shape, bent upon itself to form 40 an inverted yoke, the legs of which are extended or enlarged at their free ends to form a supporting surface or base of relatively large area; and these enlarged or extended portions or feet are spread apart to increase 45 the stability of the holder. The portion which connects or bridges the upper end of the legs is constructed to permit the engagement of the watch stem therewith, and the lower portion of the watch projects into a 50 pair of pockets produced by the peculiar formation of the feet, so that the watch is maintained at all times in proper position in the holder, and is held against accidental displacement or slippage. The advantage of 55 this is that under ordinary conditions the

watch is disposed with its dial in reading position; while if the holder should be tipped over, the watch will be prevented from falling out, and the crystal will be kept from striking against the surface of 60 the support whereon the holder rests.

More particularly, the aforesaid bridge portion which straddles the watch stem projects forwardly of the holder and, hence, virtually overhangs the pockets above referred to; and the distance between the bridge and the bottoms of the pockets may be, and preferably is, such that a slight gripping pressure is thereby exerted upon the top and bottom of the watch consequent 70 upon its introduction into the holder, thus facilitating its retention in the holder. Preferably, also, the feet, or their outer portions, are so constructed as to be slightly flexed or spread apart during the insertion 75 of the watch, so that a snap action is thereby obtained. The projecting top portion or bridge is formed with a slot for the reception of the watch stem; but this slot, in the preferred form of the invention, extends 80 rearwardly instead of forwardly, so that its closed end is at the front of the stem and not at its back, the result being that the watch is in contact at opposite sides with the bridge and the legs of the holder, 85 which tends to further increase the stability of its position.

In the accompanying drawings:—

Figure 1 is a perspective view showing the preferred form of the invention and its mode 90 of use in connection with a watch, the latter being represented in dotted lines.

Fig. 2 is a front view of Fig. 1, the dotted lines indicating, in an exaggerated manner, the positions assumed by the legs of the 95 holder during the insertion or removal of the watch.

Fig. 3 is a side elevation, on a slightly reduced scale, showing the holder tipped over and illustrating the position assumed at 100 that time by the watch with relation to the supporting surface on which the holder rests.

Fig. 4 is a plan view of the blank from which the holder illustrated in Fig. 1 is constructed.

Figs. 5 and 6 are, respectively, a side elevation and a front elevation of a modified form of holder.

Referring to the drawings, it will be seen 110

that the improved stand or holder is constructed from a single strip or blank which may be of sheet material, either metal or non-metal as may be preferred, and as illustrated in Figs. 1-4, or of wire as represented in Figs. 5 and 6. In either instance, the holder comprises an upwardly-extending, substantially upright body portion and a supporting base at the foot thereof.

- 10 In the form represented in Figs. 1-4, which may be regarded for all present purposes as the one preferred, the holder takes the form of an upright or inverted yoke, the legs 1 of which converge toward each other 15 and are connected at their upper ends by a bridge-piece 2. The legs of the yoke are formed by the intermediate portions or members 1 of the blank represented in Fig. 4 and are disposed substantially in alinement, 20 while the bridge is similarly formed by the central loop-shaped portion 2 of the blank which connects the confronting inner ends of the portions 1. The base of the stand or holder is formed by the enlarged lower ends 25 3 of the legs, which ends extend both forwardly and rearwardly from the legs and constitute elongated supporting feet.

The bridge 2 mentioned above extends horizontally in a forward direction and has 30 the appearance of a loop or U, the bight of which is at the front thereof. This bridge is designed to engage the top part of the body 4 of the watch 5 and to straddle the stem 6 of the watch; and it is to be observed that by 35 reason of the above described construction and arrangement of the bridge, its bight portion extends across the front surface of the stem. The purpose and advantage of this particular arrangement will be explained 40 hereinafter.

As previously stated, the feet 3 extend both fore and aft of the legs 1. The front portions of the feet are utilized to support the lower portion of the watch and, 45 jointly with the bridge 2, to maintain the watch in proper upright reading position in the holder. To this end, the aforesaid front portions of the feet are constructed to provide or produce pockets, indicated at 7, 50 wherein the lower portion of the watch is received; and the distance between the bottoms of these pockets and the bridge 2 may be, and preferably is, slightly less than the diameter of the watch body, so that when the 55 watch is in place in the holder, there will be a slight gripping action exerted upon it; the extent of such action depending of course upon the particular distance in question and the diameter of the particular watch in use. 60 In the construction represented in Fig. 1, the pockets are located immediately at the foot of the legs 1, and the rear edges of the pockets are, in fact, constituted by continuations of the front edges of said legs. The pockets 65 are curved or concave and are of sufficient

width to enable the bottom of the watch body to conformably fit therein. Consequently, there will be an appreciable space between the front edges of the pockets and the front ends of the feet 3. Immediately 70 in advance of the pockets, the feet are slightly elevated, as indicated at 8, the rear edges of these elevated portions or projections 8 merging into the front edges of the pockets. The horizontal projection of the 75 bridge 2—that is, the extent to which it projects forwardly beyond the legs 1—is at least as great as the width of the pockets 7.

The feet 3 are caused to incline slightly 80 inward or toward each other, due to the converging arrangement of the yoke legs 1; and the front edges of the projections or lugs 8 are inclined upward and rearward, as indicated in Fig. 1. Because of the arrangement just described, it will be apparent that when 85 the stem of the watch has been inserted in the open central space or slot 9 produced by the U-shaped formation of the bridge 2, and the body 4 of the watch is moved rearwardly toward the legs, to effect the reception of its lower portion in the pockets 7, the movement 90 of the watch along the inclined edges of the projections 8 which constitute cams will tend to spread the legs away from each other; and there may also be a tendency to flex the 95 bridge 2 in an upward direction. This flexion or spreading of the legs is indicated diagrammatically and to a greatly exaggerated extent by the dotted line showing in Fig. 2.

As soon as the watch passes over the tops 100 of the projections 8, it will be free to snap into the pockets, and at the same time the legs 1 will move inwardly toward their original position indicated in full lines in 105 Fig. 2. When so positioned in the holder, the watch will be maintained in proper reading position and will be held against accidental displacement or slippage in any direction. This is due in general to the three-point contact or engagement of the holder with the watch, the body of which contacts at its bottom with the walls of the pockets 7 and at its top with the bridge 2, the latter 110 also straddling the watch stem and thus engaging the stem at opposite sides.

The fore-and-aft extension of the feet 3 relative to the holder legs has the effect of providing a supporting base of relatively large area, thus stabilizing the holder. In 120 case the holder should be tilted over accidentally, however, it will rest on the surface of the table, desk or other support at the front ends of the feet 3 and the bridge 2, as indicated in Fig. 3. But it will be 125 observed that the watch, even when in such position, will be held out of contact with the supporting surface, so that there is no danger of the watch crystal striking against such surface and being cracked or broken 130

thereby; nor is there any danger of the watch falling out of the holder, because of its retention at one end by the pockets 7 and at the other end by the looped bridge 2.

5 In the modified construction shown in Figs. 5 and 6, the holder is constructed of a single piece of spring wire of suitable gage and resiliency. The wire is bent into the same general shape as the holder of 10 sheet material represented in Fig. 1, and the corresponding parts of the wire holder are therefore indicated by the same reference numerals with the addition of the prime mark. Further description of the 15 wire holder is therefore considered unnecessary.

I claim as my invention:—

1. A watch stand, comprising an upwardly-extending body portion having a 20 stem-engaging part adjacent its upper end and a self-sustaining base at its lower end, said base embodying a pair of spaced spring supports for engagement with the body of a watch; said supports having pockets to 25 receive the lower portion of the watch and adapted to be forced laterally away from each other incidental to the engagement of the watch in said pockets.

2. A watch stand, comprising a body having spaced legs disposed at opposite sides of its vertical axis, said body being provided at its upper end with a part adapted to engage the upper part of a watch, and at its lower end with self-sustaining supporting feet adapted to engage the lower part of the watch and to stand upon a flat surface, the part on the upper end of said body having a stem-receiving slot which opens rearwardly so that the closed end of

the slot will be disposed adjacent the front 40 surface of the stem when a watch is inserted in the stand.

3. A watch stand, comprising a yoke, the legs of which are adapted to contact at their front edges with the back of a watch and 45 are provided at their lower ends with self-sustaining supporting feet adapted to stand upon a flat surface; the bridge portion of the yoke adapted to engage the top part of the watch and having a slot to receive the 50 watch stem and which is closed at its front end, so that said end will be disposed adjacent the front surface of the stem when a watch is inserted in the stand.

4. As a new article of manufacture, a 55 blank for a yoke-shaped watch stand comprising a strip of resilient sheet material embodying a pair of intermediate portions disposed substantially in alinement with each other and adapted to form the legs of 60 the yoke, a U-shaped central portion connecting the adjacent inner ends of the intermediate portions and forming the bridge of the yoke, and enlargements at the outer ends of the intermediate portions to form 65 supporting feet for the yoke legs.

5. A watch stand, comprising an upwardly-extending body portion having a 70 stem-engaging part adjacent its upper end and a pair of spaced spring supports adjacent its lower end engageable with the body of a watch; said supports adapted to be forced laterally away from each other by the act of effecting such engagement and having cam portions for engagement with 75 the watch to produce said lateral movement.

In testimony whereof I affix my signature.
HENRY C. KARR.
